UNITED STATES PATENT OFFICE.

FRANCIS W. D'OLIER, OF MOORESTOWN, NEW JERSEY.

PENCIL.

Application filed October 26, 1921. Serial No. 510,493.

To all whom it may concern:

Be it known that I, FRANCIS W. D'OLIER, a citizen of the United States, residing at Moorestown, in the county of Burlington and State of New Jersey, have invented certain new and useful Improvements in Pencils, of which the following is a specification.

This invention relates to pencils and pertains particularly to magazine pencils and to pencils for carrying extra lead.

One of the objects of the invention is to provide a compact simple device which will be durable and easily operated, and at the same time inexpensive to manufacture.

The features of the invention provide for the utmost simplicity in the arrangement and construction of parts, thus reducing the chance of breakage and binding of the parts to a minimum. The relative simplicity of the parts makes it possible to dispense with the need for special manufacturing machines.

The operating mechanism is similar to that new form as illustrated in my Patent No. 1,436,581, issued Nov. 21, 1922, in which the above general advantages are also presented. The present invention includes additional features presenting modifications of various parts. These details relate to the particular configuration of the rear end portion of the barrel, the mounting of the actuating end piece on the barrel, and the attachment of the actuating spring screw to the actuating end piece.

Another feature includes the specific spring detent and clasp for holding the parts together.

This invention also uses the important features illustrated in Patent No. 1,436,581 which give important advantages resultant from the peculiar spring feed feature which permits a cushioned effect, and prevents the breaking of lead and reduces to a minimum the tiring experienced by a writer after using a pencil in continuous writing.

Another feature is the particular way in which the configuration of the barrel is used in combination with the transparent cover and the end cover for the point end of the pencil.

The particular configuration and relative position of the parts is set forth in the following specification and claims, and il-

lustrated in the accompanying drawing, in which:

Figure 1 is an enlarged view of a section taken centrally and longitudinally through the pencil; 60

Figure 2 is a side view of the unitary combined actuated screw and plunger, as removed from the pencil;

Figure 3 is a side view of the rear end piece removed from the barrel and showing the slot therein; 65

Figure 4 is a sectional view taken on line 4-4 of Figure 1 and looking toward the point of the pencil; and

Figure 5 represents an end view of the barrel of the pencil with the actuating spring screw removed and showing the actuated screw and plunger within the barrel and the plunger within the central tube. 70

Figure 6 represents an end view of a modification of the barrel and actuated screw showing the lateral projection from the screw in engagement with a grooved guideway in the barrel. 75

Referring in detail to the drawing, 1 indicates the barrel of a pencil of the type described enlarged considerably in order to most clearly illustrate the relative positions of the parts. 1^a indicates the rear end of the barrel, and 1^b indicates the front end of the barrel, and the front end is provided with the threaded outer portion 1^c. The rear end portion of the barrel for a half inch or more of its length is provided with an enlarged bore providing the projecting flange wall 1^d. 80

A combined actuating and rear end member 2 is shown in its removed position in Figure 3, and in Figure 4 as mounted within the enlarged bore of the rear end portion of the barrel 1. The rear end member 2 is provided with a reduced cylindrical or tubular portion 2^a which is adapted to slide into the enlarged bore of the barrel 1 in a manner hereinafter described and claimed as a telescopic connection. 85

An inclined sloping surface and connecting wall 2^b is provided to have a surface corresponding to the end surface of the barrel end 1^a, and in the present adaptation is shown as a beveled surface. 1^a and 2^b might be formed at right angles to their respective adjacent surfaces. At the extreme inner end of the actuating end piece 2 90

is the annular flange 2^c. A slot 2^d is cut in the wall 2^a lengthwise thereof and extends 95

to the flange 2^c. The actuating end piece 2 is provided with a longitudinal slot 2^e which extends from the flange 2^c to the outer end of the actuating end piece 2. 100

The actuating end piece 2 is provided with a longitudinal slot 2^f which extends from the flange 2^c to the outer end of the actuating end piece 2. 105

The actuating end piece 2 is provided with a longitudinal slot 2^f which extends from the flange 2^c to the outer end of the actuating end piece 2. 110

ing from the surface 2^b for a short distance toward the flange 2^c, and thence recurved and terminating in the closed end 2^e. The particular function of the flange 2^c and the slot 2^d will be further explained.

The front end is provided with a screw threaded fastening cap 3 which has a rear portion 3^a with threads adapted to engage the threads 1^c of the barrel. Tapering forwardly from the portion 3^a, the inner walls of the tip are indicated at 3^b, and this tapered portion extends into a more sharply inclined part indicated at 3^c. The rear end of the cap is provided with a square cut shoulder indicated at 3^d, corresponding to the shoulder 1^d formed by the enlarged outer surface of the rear end of the barrel. The extreme tip of the pencil is indicated at 3^e, and a restricted bore for providing a tight sliding fit for the lead is indicated at 3^f. Between the point 3^e and the bore 3^f there is provided a cylindrical portion having the walls 3^g which provides a loose sliding fit for the central guide tube as will be described. Between the walls 3^g and immediately adjacent the entrance to the bore 3^f is the annular inclined surface 3^h against which the central tube is adapted to rest in order to position the tube centrally and bring the bore of the tube into alignment with the bore 3^f.

A transparent sleeve 4 of celluloid or other suitable material is loosely fitted over the length of the barrel 1 and held in position by the shoulder 1^d and the shoulder 3^a. Preferably the cylinder 4 has walls of the same thickness as the width of these shoulders, so that the assembled pencil may provide a smooth exterior. Between the barrel 1 and the cylinder 4 suitable advertising material may be inserted for display through the cylinder 4, or designs for artistic effect or advertising material may be carved on the outer surface of the barrel 1 and thus made visible through the cylinder 4, although protected from actual wear by the outer transparent covering. Claims to the transparent sleeve feature are presented in my application Serial No. 587,708, filed September 12, 1922, a divisional application from Serial 510,492 (now patent 1,436,581).

Detent means is provided for holding the actuating end piece in position at the rear end of the barrel by the member 5 which serves as a combined spring clasp and spring detent. This member is illustrated as formed of a recurved piece of metal secured to the exterior of the barrel 1 at the point 5^a by a suitable rivet. From this fastening point an arm 5^b extends along the surface of the barrel 1 and terminates with a lateral projection 5^d which extends inwardly through the barrel to engage the telescoping end of the member 2. As illustrated, the end 5^c engages the rear face of the

flange 2^c to prevent the accidental withdrawal of the actuating end piece from the barrel. The end 5^c is provided with a beveled inner face to facilitate a sliding movement of the flange 2^c past the locking end 5^e. In order to withdraw the actuating end piece, the yielding member 5^b may be raised from the barrel sufficiently to release the flange 2^c. Instead of engaging the flange, a groove might be provided in the portion 2^a, and the projecting end 5^c might fit into the bottom of this groove. Such a construction would make possible also the same relative rotary movement between the end piece 2 and the barrel 1 which is used to actuate the lead plunger, as will be described. The clasp end of the member 5 is indicated at 5^d as extending toward the barrel of the pencil to provide a yielding engagement with any supporting object, such as clothing. Thus this part of the pencil serves as a combined clasp and detent, rendering unnecessary the use of two or more parts to perform the same functions.

A central partition 6 is securely fixed within the barrel by brazing, soldering, or other suitable means, and divides the inner bore of the barrel into a front and rear chamber, the front chamber being a magazine for extra leads, and the rear chamber containing the actuating screws. The partition 6 has an axial opening 6^a for the reception of the guide tube which will be described.

Guide tube 7 is rigidly mounted within the opening 6^a by brazing or soldering, and is thus fixed with respect to the barrel. The tube 7 has the extreme front end 7^a projecting beyond the end of the barrel and adapted to engage the inclined wall 3^b of the tip. The rear portion of the tube on the opposite side of the partition 6 is indicated at 7^b, and is provided with a slot through the wall thereof, as indicated at 7^c, this slot extending from the rear end of the guide tube substantially all of the way to the partition.

The actuating helically coiled spring screw member 8 substantially fills the diameter of the bore of the barrel and extends substantially the full length of the rear chamber. It will be noted that the member 8 is free to revolve within the circular walls of the barrel; and that the lateral portions of the spring 8 are loosely positioned within the barrel; and that the coils or turns of the member 8 are positioned apart a distance substantially as great as the cross section of the material of the spring. The extreme rear end 8^a of the member 8 extends into the slot 2^d in a radial direction. The end 8^a is slipped into the closed notched end 2^e so that by turning the actuating end piece 2 the screw 8 may likewise be turned. The distance from the closed end 2^e to the adjacent face of the partition 6 is slightly less

than the total length of the spring 8 in its freely extended position. When the end 8^a is fitted into the notched closed end 2^e the spring screw 8 is slightly compressed and the inner end 8^b is pushed slightly against the face of the partition 6, and the member 8 is thus secured against any unnecessary play lengthwise within the pencil barrel.

The combined actuated screw and plunger 9 is illustrated in its removed position in Figure 2, and in its assembled position with the other parts in Figure 1. This structure is peculiar in that the plunger rod is continuous and formed in one piece with the actuated screw portion 9^a. The member is inserted in the rear end of the barrel by fitting the rod 9 into the slotted guide tube 7^b. A right angle shoulder 9^a extends from the straight rod 9 to the helical turn of the actuated screw part 9^a. The portion 9^b is shown clearly in Figure 5. The right angle shoulder 9^b extends through the open slot 7^c and is prevented from turning by the walls of this slotted opening. Comparing the respective size and pitch of the turns of the helical screw portions 8 and 9^a, as shown in Figures 1 and 2, it will be noted that these dimensions are substantially the same as may be observed by comparing the distance A—B, in Figure 1, with the distance C—D, in Figure 2. Referring to Figure 1 it will be noted that the turns of the member 9^a substantially fill the spaces between the adjacent turns of the member 8.

The structure is assembled by first inserting a combined plunger 9 and actuated screw 9^a within the slotted tube so that the shoulder 9^b extends through the slot. The actuating end piece with the slotted opening 2^b is fitted over the rear end of the spring 8 so that the end 8^a projects through 2^b. 8 is then inserted into the rear end of the barrel 1 until it engages the coils 9^a of the plunger. The end 8^a is slipped into the closed notched end 2^e, and the actuating end piece 2 is moved into the enlarged portion of the barrel 1 until the flange 2^c slips past the detent 5^e. The pencil is now assembled and by turning 2 clockwise or counter-clockwise, the plunger is moved back and forth. To disassemble the rear end of the pencil the spring detent 5^b is pulled outwardly to disengage 5^e from 2^c, after which the actuating end piece may be withdrawn for examination or repair, and then replaced as before. Leads are normally inserted by removing the front end cover 3 and slipping each additional lead as used into the front end of the tube 7, and then replacing the cap 3. Adjustment of the member 2 draws the plunger 9 forward or backward, and the lead is forced from the guide tube 7 through the bore 3^f into position for use at the tip of the pencil 3^e.

The extreme end of the actuating end

piece 2 may be provided with an inwardly extending flange for holding an eraser, as indicated at 2^d. The surface of the portion 2 may be knurled to provide a non-slipping surface. The slot 2^d may be cut or stamped from the portion 2^a very cheaply, and the flange 2^c may be struck up radially as shown at the end of this piece, or it may be positioned at any point lengthwise of the surface 2^a by crimping or other usual stamping operation.

In Figure 6 is illustrated an alternate form of actuated screw and plunger in which the rear end of the screw projects radially and laterally as indicated at 9^e to provide a lug or tip adapted to engage a longitudinal groove 1^e formed in the wall of the barrel 1. This arrangement assists in preventing the rotation of the plunger and any twisting of the split tube 7^b due to such possible rotation. The same effect as provided by the use of the groove 1^e may also be provided if a slot is cut completely through the wall 1, and in either arrangement the projection 9^e need not be longer than the thickness of the wall 1. The groove or slot should extend the length of the rear chamber from the rear end of the smaller bore of the barrel to the partition 6.

Further strengthening means for the tube 7 may be provided by providing an additional portion similar to 6 but spaced therefrom, or by providing a relatively wide partition.

The arrangement of the working parts provides a resilient spring-like yielding movement to the lead which is desirable for easy writing. The simplicity of the parts has provided an inexpensive construction, even less expensive than that form illustrated in the Patent No. 1,436,581, and one which is not subject to breakage or repeated adjustments. The materials may be made from any readily worked metal, and the substitution of one material over another will not depart from the scope of this invention.

I claim:

1. In a pencil, a barrel having a front end and a rear end, a front end piece secured to said front end, a rear end piece having a telescopic connection with said rear end of said barrel and a coacting surface in the side wall thereof, and an actuating helically coiled spring screw member rotatably mounted within said barrel and having one end thereof projecting radially and in engagement with said coacting surface and thus being fixed to said rear end piece.

2. In a pencil, a barrel having a front end and a rear end, a front end piece secured to said front end, a rear end piece having a telescopic connection with said rear end of said barrel and having a recess in the wall

thereof, and an actuating helically coiled spring screw member rotatably mounted within said barrel and having one end thereof projecting laterally into said recess and thus being detachably secured to said rear end piece.

3. In a pencil, a barrel having a front end and a rear end formed as a tube with a continuous side wall therearound, a front end piece secured to said front end, a rear end piece having a telescopic and rotatable connection with said rear end of said barrel, an actuating helically coiled spring screw member rotatably mounted within said barrel and having one end thereof secured to said rear end piece, and a detent engaging said rear end piece and said barrel and movable with respect to both said barrel and said rear end piece and permitting relative rotation but not lengthwise movement of these parts.

4. In a pencil, a barrel having a front end and a rear end and a main bore extending therethrough, the walls of said barrel adjacent the rear end thereof being enlarged and forming a secondary and larger bore adjacent the rear end, a rear end piece having a barrel portion adapted to project within said secondary bore and having a rotatable engagement with said barrel, detent means engaging said rear end piece and said barrel and movable with respect to both said barrel and said rear end piece and permitting relative rotation but not accidental lengthwise movement of these parts, an actuating helically coiled spring screw member rotatably mounted within said barrel and having one end thereof secured to said rear end piece, and an actuated coiled screw member positioned in engagement with said actuating screw and adapted to travel in both said bores.

5. In a pencil, a barrel having a front end and a rear end and a main bore extending therethrough, the walls of said barrel adjacent the rear end thereof being enlarged and forming a secondary and larger bore adjacent the rear end, a rear end piece having a barrel portion adapted to project within said secondary bore and have a rotatable engagement with said barrel, detent means engaging said rear end piece and said barrel and movable with respect to both said barrel and said rear end piece and permitting relative rotation but not accidental lengthwise movement of these parts, an actuating helically coiled spring screw member rotatably mounted within said barrel and having one end thereof detachably secured to said rear end piece, and an actuated coiled screw member positioned in engagement with said actuating screw and adapted to travel in both said bores.

6. In a pencil, a barrel having a front end and a rear end and a main bore extending

therethrough, the walls of said barrel adjacent the rear end thereof being enlarged and forming a secondary and larger bore adjacent the rear end, a rear end piece having a barrel portion adapted to project within said secondary bore, an annular flange on the inner end of said rear end piece, a detent member movable with respect to both said barrel and said rear end piece and positioned to normally engage the rear face of said flange and prevent the withdrawal of the same from said barrel, an actuating helically coiled spring screw member rotatably mounted within said barrel and having one end thereof secured to said rear end piece, and an actuated coiled screw member positioned in engagement with said actuating screw and adapted to travel in both said bores.

7. In a pencil, a barrel having a front end and a rear end and a main bore extending therethrough, the walls of said barrel adjacent the rear end thereof being enlarged and forming a secondary and larger bore adjacent the rear end, a rear end piece having a barrel portion adapted to project within said secondary bore, an annular flange on the inner end of said rear end piece, a yieldable detent member extending through said barrel and positioned to normally engage the rear face of said flange and prevent the withdrawal of the same from said barrel, and an actuating helically coiled spring screw member rotatably mounted within said barrel and having one end thereof secured to said rear end piece.

8. In a pencil, a barrel having a front end and a rear end, a front end piece secured to said front end, a rear end piece having a telescopic connection with said rear end of said barrel, said rear end piece having a slot therein extending lengthwise thereof, thence recurved and terminating with an inner end between the end of said rear end case, and an actuating helically coiled spring screw member rotatably mounted within said barrel and having one end thereof detachably secured in the inner end of said slot.

9. In a pencil, a barrel having a front end and a rear end formed as a tube with a continuous side wall therearound, a front end piece secured to said front end, a rear end piece having a telescopic and rotatable connection with said rear end of said barrel, an actuating helically coiled spring screw member rotatably mounted within said barrel and having one end thereof secured to said rear end piece, and detent means carried by said barrel and movable with respect to both said barrel and said rear end piece and in releasable engagement with said rear end piece and permitting relative rotation but not lengthwise movement of the rear end piece with respect to the barrel when said detent means is in engagement with said rear end piece.

10. In a pencil, a barrel having a bore

therein and formed as a tube with a continuous side wall therearound, an end piece in telescopic rotatable engagement with said barrel and having a bore of the same diameter as the bore of said barrel and in alignment therewith, a coiled actuating screw engaging the walls of both bores, and an actuating coiled screw member positioned in engagement with said actuating screw and adapted to travel in both said bores.

11. In a pencil, a barrel having a bore therein and formed as a tube with a continuous side wall therearound, an end piece in telescopic rotatable engagement with said

barrel and having a bore of the same diameter as the bore of said barrel and in alignment therewith, the walls of the bores of said barrel and said end piece extending as a substantially continuous cylindrical surface, a coiled actuating screw positioned within said bore and engaging the cylindrical walls thereof, and an actuating coiled screw member positioned in engagement with said actuating screw and adapted to travel in both said bores.

20 In testimony whereof I affix my signature.

25 FRANCIS W. D'OLIER
